UNITED STATES PATENT OFFICE.

ALBERT V. BAXTER, OF WARRINGTON, ENGLAND, ASSIGNOR TO ERASMIC COMPANY LIMITED, OF WARRINGTON, ENGLAND, A CORPORATION OF GREAT BRITAIN.

DESIGN FOR A BOTTLE.

Application filed February 2, 1921. Serial No. 442,000. Term of patent 3½ years.

To all whom it may concern:

Be it known that I, ALBERT VICTOR BAXTER, a citizen of Great Britain, and resident at Waratah, Lower Walton, Warrington, in the county of Lancaster, England, have invented a certain new, original, and ornamental Design for Bottle, of which the following is a specification.

My new design is illustrated in the accompanying drawing, in which:

Figure 1 is a front elevation of the design.

Figure 2 is a side elevation of the design.

Figure 3 is a plan view thereof.

I claim:

The ornamental design for a bottle, as shown.

A. V. BAXTER.
